(57)

CLAIM

We claim the ornamental design for a middle region of a game racquet with separate head and handle portions, as shown and described.

(73) Assignee: **Wilson Sporting Goods Co.**

DESCRIPTION

(**) Term: **14 Years**

(21) Appl. No.: **29/160,026**

(22) Filed: **May 2, 2002**

Related U.S. Application Data

(63) Continuation-in-part of application No. 09/849,965, filed on May 4, 2001.

FIG. 1 is a front view of a middle region of a game racquet with separate head and handle portions of the present invention.

(51) **LOC (7) Cl. 21-02**

FIG. 2 is an enlarged front view of the region shown in FIG. 1.

(52) **U.S. Cl. D21/729**

FIG. 3 is a side view of the region shown in FIG. 1.

(58) **Field of Search** D21/729-733; 473/524, 533, 535, 545

FIG. 4 is a bottom view of the region shown in FIG. 1 including broken (dashed) lines for the purpose of illustrating environmental elements only environmental.

(56) **References Cited**

FIG. 5 is a bottom view of the region shown in FIG. 1 without broken lines illustrating environmental elements.

U.S. PATENT DOCUMENTS

FIG. 6 is a top view of the region shown in FIG. 1 including broken (dashed) lines for the purpose of illustrating environmental elements only environmental.
